ELECTRIC DRY SHAVER

Kazuhiko Kubo and Taro Kasagi, Ibaraki-shi, Japan, assignors to Hitachi Maxell, Ltd., Osaku-fu, Japan

Filed Mar. 13, 1968, Ser. No. 10,948

Term of patent 7 years

Int. Cl. D28—03

U.S. Cl. D95—3

FIG. 1

FIG. 2

FIG. 3

FIG. 4

FIG. 5

FIG. 6

FIGURE 1 is a rear perspective view of the electric dry shaver showing our new design;
FIGURE 2 is a front elevational view thereof;
FIGURE 3 is a top plan view thereof;
FIGURE 4 is a side view of one side thereof;
FIGURE 5 is a side view of the other side thereof; and
FIGURE 6 is a bottom plan view thereof.

The dotted line showing in FIGURE 1 is for illustrative purposes only.

Additionally, while the pattern on the shaver cutting head is shown only in part in FIGURES 1, 2 and 3, it should be understood that in actuality this pattern covers the entire cutting head and has been shown in part only for simplicity of illustration.

We claim:

The ornamental design for an electric dry shaver, substantially as shown and described.
